UNITED STATES PATENT OFFICE.

GEORGE H. WOODHOUSE, OF SEATTLE, WASHINGTON, AND WILFRED L. BROWN, OF SAN FRANCISCO, CALIFORNIA.

AMALGAMATOR.

1,034,051.

Specification of Letters Patent. Patented July 30, 1912.

Application filed May 22, 1911. Serial No. 628,775.

To all whom it may concern:

Be it known that we, GEORGE H. WOODHOUSE and WILFRED L. BROWN, citizens of the United States of America, and residents 5 of the city of Seattle, in the county of King and State of Washington, and of the city of San Francisco, in the county of San Francisco and State of California, respectively, have invented certain new and useful 10 improvements in Amalgamators, of which the following is a specification.

Our invention relates to apparatus for extracting precious metals, and has for one of its objects the provision of a novel construction through the medium of which the comminuted ore and metalliferous slimes are subjected to the action of water, controlled in a novel manner for obtaining current effects of greater value.

20 A further object resides in a novel provision for introducing the fluid into the separating chamber.

Other objects will be set forth as our description progresses and those features of 25 construction, arrangements and combinations of parts on which we desire protection, succinctly defined in our annexed claims.

Referring to the accompanying drawing, wherein like numerals of reference indicate 30 like parts throughout: Figure 1 is a plan of our invention. Fig. 2 is a side elevation thereof, portions being broken away. Fig. 3 is a vertical transverse section, and Fig. 4 is a fragmentary detail view illustrating 35 more particularly one of the deflectors and showing by broken lines two positions of adjustment thereof.

In carrying out our invention, we provide a separating chamber, as 1, in which 40 is arranged a fixed central partition 2, the same dividing said chamber into the branches 1', 1'' which are connected at one end portion by a passage-way 3, conveniently provided by spacing one end of partition 2 from the adjacent end wall of the chamber.

Extending throughout the length of chamber 1 and lying beneath partition 2, is a fluid discharge head 5, provided at its 50 opposite sides with continuous discharge openings or slits 4 extending for its entire length and each opening into a respective branch of chamber 1. Head 5 conveniently comprises upper and lower sections 5', 5'', the former being concave and fixedly se-

cured to the end walls of chamber 1, as shown, with its depending side walls spaced from section 5'' to provide the elongated openings 4 from which the water will discharge into each branch 1', 1'' in a thin mass 60 or sheet, against suitable deflectors 6, of respective series, each of which series of deflectors is set to direct the water toward a respective end of chamber 1, thereby insuring a more thorough disseminating action 65 on the pulp or material to be treated, which latter with the impelled water, through the medium of said deflectors, is caused to impinge suitable amalgamating plates 7 with a spirally revolving movement in each of 70 the chamber branches 1', 1''. Head section 5' tapers toward passage-way 3 to thereby gradually reduce the internal cross sectional area of the discharge head 5 from its forward end, by which construction the water 75 will discharge with substantially uniform force for the entire length of the head.

To permit of deflectors 6 being adjusted to vary their angle of deflection, we adjustably mount each series thereof on respective 80 supports 8 by screw bolts 9 which pass through base lugs of the deflectors and have screw threaded engagement in the underlying support. Supports 8, as now considered, comprise bars arranged at the side 85 edges of head section 5'' and secured to the end walls of chamber 1, as shown.

By providing deflectors 6 in the manner described, we are enabled to nicely determine the duration of the treatment, suiting 90 it to the quality and quantity of material fed to chamber 1. For example, these deflectors 6 adjacent partition 2 may be set at less angularity than those at passage way 3, so that the heavier materials fed will be 95 well worked, while at the same time a current is induced which carries away the lighter particles. Amalgamating plates 7 which are removable, extend upwardly from supports 8 over the curved side walls of 100 chamber 1 and are removably held thereon by suitable engaging hook parts 10.

In operation, fluid under pressure is supplied to head 5, through a pipe 12 which may be connected to a pump 11, and the 105 material to be treated then being fed, into the branch 1' of chamber 1 at the forward end thereof, is caught by the water and caused to travel in a spiral path over the adjacent amalgamating plate 7 toward the 110

passage-way 3. The material carried by the water when passage-way 3 is reached is drawn through the latter for further treatment, being caught by the spirally moving mass in branch 1'' and again advanced toward the forward end of chamber 1, wherein an overflow port 12' is provided. Further, pump 11 is preferably provided with an intake pipe 14 which is connected with this end portion of branch 1'', as shown, thereby serving to promote circulation. By discharging water into chamber 1, in the manner hereinbefore set forth, all of the material introduced into the chamber will be directly acted upon as contra-distinguished from prior constructions wherein a discharge head formed with series of discharge orifices is provided.

Having thus described our invention, what we claim as new, and desire to secure by Letters Patent of the United States of America, is:—

1. An amalgamator comprising an elongated chamber, a delivery head having a discharge opening extending along its length, said head being located at the bottom and at one side of said chamber, the discharge opening of said head being directed toward the opposite side of said chamber, and a series of vertically arranged plates at the bottom of said chamber disposed lengthwise of the latter immediately

in front of the opening of said head and being adjustable as to angle longitudinally of said chamber.

2. An amalgamator comprising an elongated chamber, provided in its side at one end portion thereof with a delivery opening, a delivery head having a discharge opening extending along its length, said head being located at the bottom of said chamber and at the last named side thereof, the discharge opening of said head being directed toward the opposite side of said chamber, a series of vertically arranged plates at the bottom of said chamber immediately in front of the discharge opening of said head and disposed lengthwise thereof, and means for securing said plates for independent adjustment as to angle longitudinally of said chamber.

Signed at Seattle, Washington, this 5th day of May, 1911.
